CLAIM

The ornamental design for a mouse, as shown and described.

DESCRIPTION

FIG. 1 is a front perspective view of a mouse showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depicting portions of the mouse form no part of the claimed design.
